UNITED STATES PATENT OFFICE.

OLIVER B. SHALLENBERGER, OF ROCHESTER, ASSIGNOR TO GEORGE WESTINGHOUSE, JR., OF PITTSBURG, PENNSYLVANIA.

CIRCUIT-CONTROLLING APPARATUS FOR ELECTRIC-LIGHTING CIRCUITS.

SPECIFICATION forming part of Letters Patent No. 383,661, dated May 29, 1888.

Application filed March 28, 1887. Serial No. 232,067. (No model.)

To all whom it may concern:

Be it known that I, OLIVER B. SHALLENBERGER, a citizen of the United States, residing in Rochester, Beaver county, in the State 5 of Pennsylvania, have invented certain new and useful Improvements in Circuit-Controlling Apparatus for Electric-Lighting Systems, of which the following is a specification.

The invention relates to an organization of 10 circuits and apparatus to be employed at the central stations of electric-lighting systems for securing any desired circuit-connections between different pairs of main lines or supply-conductors and different generators at will; 15 and the object of the invention is to provide convenient apparatus for this purpose which may be used without producing any noticeable effect upon the lights during the changes in the connections, and which is easily controlled. 20

The invention will be described in connection with the accompanying drawings, in which—

Figure 1 is a diagram illustrating the general organization of circuits, and Figs. 2 and 25 3 are respectively a side elevation and a front view of the switch devices.

Referring to Fig. 1, A', A², and A³ represent three independent electric generators, 30 which may in this instance be conveniently considered as being alternate-current generators. The poles of the generator A' are respectively connected by conductors 1 and 2 with supply-conductors L' and L². The generator A² is connected by conductors 3 and 4 with supply-conductors L³ and L⁴, and the generator A³ by conductors 5 and 6 with the supply-conductors L⁵ and L⁶.

A series of primary conductors, or conductors leading to converters or other suitable apparatus, are represented in pairs at P' P², P³ P⁴, P⁵ P⁶, and P⁷ P⁸. These are supposed to lead to independent apparatus; but it may be desired to connect them with any one of the different generators, according to the different circumstances under which the system is to operate at different times. The conductor P' is connected with a contact-strap, B', and the conductor P² with a similar strap, B². The 45 50 strap B' is provided with three insulated contact-disks, b', b², and b³, with which it may be

connected by suitable switch-plugs, as shown at c'. The disks b', b², and b³ are respectively connected with the lines L', L³, and L⁵, which may, for convenience, be considered as positive conductors, or conductors having currents of the same character at any given time. Similar disks, b⁴, b⁵, and b⁶, are applied to the strap B², and these are respectively connected with the conductors L², L⁴, and L⁶. The switch- 55 plug c² shows the strap B² as connected with disks b⁵. Thus the lines P' and P² are shown as connected, respectively, with the conductors L³ and L⁴. By changing the position of the pins c' and c² the lines P' and P² may be 60 connected with either of the other pairs of conductors. 65

In connection with the lines P³ and P⁴ the same system of connections is shown, different forms of switches being illustrated. These each 70 consist of a movable arm, B³ B⁴, respectively connected with the lines P³ and P⁴, each provided with three contact-plates, as shown at b⁷ b⁸ b⁹ and b¹⁰ b¹¹ b¹². The connections are essentially the same as described with reference 75 to the lines P' and P², and by moving the switch-arms the lines P³ and P⁴ may be connected with any pair of conductors, L' L², L³ L⁴, or L⁵ L⁶. Switches S', S², and S³ may be employed for connecting the different generators in multiple arc in an evident manner. 80

For the purpose of securing convenient connections and allowing for changes in the connections without injuring the contacts and without producing false connections, the device illustrated in Figs. 2 and 3 is employed. This consists of a support, D, carrying upon suitable studs, d' d², a yoke-shaped lever, B, provided with two contact-plates, e' and e², designed to make electrical connection with the 90 individual contact-plates b', b², b³, and b⁴, and b⁵, b⁶, b⁷, and b⁸. These last-named plates are respectively provided with contact-plates h', h², h³, &c., which are respectively connected with the conductors L' L² L³ L⁴ L⁵ L⁶ L⁷ L⁸ to 95 any desired extent. By inserting a switch-plug, c', between any pair of plates, b' and h', for instance, and the corresponding pair, b⁵ and h⁵, and then moving the switch B into contact with the plates b' and b⁵, the circuit- 100 connections will be completed from corresponding lines, L' and L², to the switch-plates e'

and e^2 of the switch B. These plates are respectively connected with the lines P' and P ^{2} . If it is desired to change the connections to the lines L ^{3} L ^{4} , for instance, then the switch-plugs are placed between the plates b^3 and h^3 and b^4 and h^4 , and the switch B is moved over the intervening contact-plates without completing any circuit-connections therewith, the plugs being removed until it arrives at plates 10 provided with the plugs c^3 c^4 , whereupon the desired circuit-connections are completed.

Instead of the exact arrangement of plugs shown, one series may be used alone, as b^5 h^5 , &c., while the contact-plates for the opposite 15 pole may remain normally connected—i. e., b^1 and h^1 may be one plate. The plugs would then interrupt the circuit in only one place when removed, instead of two.

The dotted lines show the connections made 20 by the respective contact-plates.

I claim as my invention—

1. A switch or circuit-controlling device consisting of a movable lever, two independent circuit-closing plates upon said lever, two 25 independent series of contact-plates, in contact with which the circuit-closing plates may be respectively placed, individual contact-plates adjacent to the last-named contact-plates, and switch-plugs or circuit-closing devices adapted to place the individual contact-plates in connection with their respective contact-plates at will.

2. A circuit-controlling switch consisting of two independent circuit-closing plates, two 35 independent series of contact-plates, in contact with which the respective circuit-closing plates may be placed, corresponding series of independent contact-plates, one or both of which series are normally electrically insulated 40 from the first-named contact-plates, switch-plugs or circuit-closing devices for completing the connections between any two of the first-named contact-plates and their corresponding insulated contact-plates, and a 45 lever or support for moving the circuit-closing plates into contact therewith.

3. In a system of electrical distribution, the combination of an outgoing and return wire, two circuit-closing plates with which said wires are respectively connected, two series 50 of contact-plates arranged in pairs, means for moving said circuit-closing plates into contact with different contact-plates of said series simultaneously, pairs of supply-conductors, and coupling devices for completing the connections of any pair of contact-plates with a corresponding pair of supply-conductors at will, substantially as described.

4. The combination of the switch B, the plates e^1 and e^2 , carried thereby, the two series of contact-plates b^1 b^2 , &c., and b^5 b^6 , &c., and their corresponding plates, h^1 h^2 , &c., and h^5 h^6 , &c., and conductors leading from the latter, substantially as described.

5. The combination of the pivoted lever B, 65 the contact-plates e^1 and e^2 , carried thereby, the contact-plates h^1 h^2 , &c., and h^5 h^6 , &c., arranged in curved series, and the corresponding insulated plates with which said plates are substantially adapted to be connected, 70 as described.

6. The combination, with two or more generators, of multiple circuit-closing plates, respectively constituting the terminals of the generators, a series of contact-plates for each 75 of said circuit-closing plates, into contact with which the latter may be moved, a second series of contact-plates, one plate being provided for each of the first-named contact-plates, coupling devices for connecting the second contact-plates with the respective first-named plates, main lines connected with the respective second contact-plates, and independent switches for connecting the generators in multiple arc circuit. 80

In testimony whereof I have hereunto subscribed my name this 21st day of March, A. D. 1887.

OLIVER B. SHALLENBERGER.
